UNITED STATES PATENT OFFICE.

JOHN C. POETZ, OF ST. PAUL, MINNESOTA.

SHUTTER OPENING AND CLOSING DEVICE.

Application filed April 28, 1926. Serial No. 105,143.

This invention relates to means for opening and closing window shutters, and the main object is to enable a person in a room to open and close and hold open or closed an outside shutter without opening the regular window or such storm window or screen as may be disposed inside of the shutter.

In the accompanying drawing:

Fig. 1 is an outside elevation of a portion 10 of a house wall and window equipped with my invention.

Fig. 2 is a section on the line 2—2 in Fig. 1.

Fig. 3 is a right hand edge view of Fig. 1.

Fig. 4 is a view as on line 4—4 in Fig. 3.

Fig. 5 is Fig. 2 modified as may be required for walls having a brick veneer, or being otherwise of special thickness.

Fig. 6 is a detail side view of one of the 20 links in the shutter opener.

Fig. 7 is the upper edge of Fig. 6.

Fig. 8 is the lower edge of Fig. 6.

Fig. 9 is a section on line 9—9 in Fig. 7.

Referring to the drawing by reference 25 numerals, 12 designates a house wall in which is secured a window frame 13 having a sill 14 and a lintel 15. Mounted in said frame is a regular house window 16, a screen 17 and an outside shutter sash 18 hinged at 30 19 to the outside window casing 20 and having the usual tilttable slats 21 trunnioned at 21^a.

Now to be able to open and close said shutter without disturbing the window and 35 the screen, I provide a bendable actuating rod composed of a handle piece 22 and a series of links 23 pivoted together at 24 to form an arch the outer end of which is pivoted at 25 to a bracket 26 fixed on the 40 lower hinge member 19^a of the shutter. Each link has a shoulder 27 meeting a similar shoulder on the next link so as to cause the links to form a segment with a certain radius from the pintle of the hinge 19 as 45 its center. The adjacent wall portion has an aperture 28^a for the link rod and its handle piece 22 to slide in while the shutter is being swung open or closed by manipulation of the handle piece 22. To make said sliding movement more easy and accurate the link rod is guided between rollers 29 in a channel-shaped bracket 30 secured by screws 31 in the aperture or guide 28^a in the wall.

As a locking means for the actuating rod 50 23—28 I secure upon the inside apron 33 (see Fig. 4) a bracket 34 having a hole 35

for the rod, and adjacent the rod I pivot at 36^a on the bracket an eccentric or cam 36 having near its longest radius a finger catch 37 by which to turn it and to help giving it a tendency to rest against the adjacent edge of the actuating rod so as to engage and hold it with the shutter either open or closed. To further insure such engagement the cam is formed with several peripheral 65 edges 38 (see Fig. 2) adapted to engage in notches 39 in the handle piece 22 when the shutter is closed, or in notches 40 in one of the links 23 when the shutter is to be held open, and when thus held open the handle 70 piece 22 is folded at its joint 41 (see Figs. 2 and 4) and folded close to the apron 33, as shown in Fig. 4.

In Fig. 2, 42 indicates a certain form of hinges for the screen sash 17^a but as such 75 hinging is described and claimed in another application of mine filed simultaneously herewith the same need not be herein further described.

If the device herein described is to be 80 used in a frame house having its walls thickened by brick veneer or if the walls be made altogether of brick or stone, my device must be modified to accommodate the extra thickness of the wall. Such modification is believed to be sufficiently indicated in Fig. 5 85 where the hinges 19 are offset at 19^b to allow the shutter to be folded back as 18 against the outer side of the extra thick wall 12^a. In this case the actuating rod will have more 90 links and be altogether longer than when used in a common frame house wall.

The cell construction of the thick wall in Fig. 5 being already covered by a pending application of mine it need not be herein 95 described. Fig. 5 shows however that my present shutter opener and closer is applicable also in walls of such construction.

What I claim is:

1. The combination with a house wall and 100 a window frame therein and window sashes in the frame and a shutter hinged to fold toward the outside of the wall when opened, of a shutter opening and closing device comprising an actuating rod slidable through 105 an aperture in the wall below the window sill and having its outer portion formed of knee-jointed links adapted to form a horizontally curved segment, the outer end of said segment having pivotal connection with 110 the shutter and the other end having a handle piece operable from within the house,

a channeled bracket secured in the aperture guiding the rod at the point where it changes in the wall and having anti-friction rollers from straight to segmental position.

5. 2. The structure specified in claim 1, in which the links of the rod are segmental and the guiding rollers are so arranged at

opposite sides of the rod that each link is bound to slide in the line of its own segment at a predetermined radius from the center ¹⁰ of the segment.

In testimony whereof I affix my signature.

JOHN C. POETZ.
